UNITED STATES PATENT OFFICE

FREDERIC W. PLUMB, OF WEST READING, PENNSYLVANIA, ASSIGNOR TO THE NARROW FABRIC CO., OF WEST READING, PENNSYLVANIA, A CORPORATION OF PENNSYLVANIA

BRAIDING MACHINE

Application filed September 14, 1929. Serial No. 392,526.

The present invention consists of improved mechanism for producing a braided fabric having a varying cross section formed by a periodic contraction of a flat filler.

The process of braiding a covering upon a filler, and machines for accomplishing this end are old, and the present invention consists of novel mechanism, which is in the nature of an attachment adapting machines now in use for the aforesaid purpose.

The machines customarily used, employ in connection with feed and take off mechanism, means for guiding the filler tape to and past the braiding point, and thread or yarn carriers which by their movement apply a braiding to the filler tape as it passes this point.

When the filler tape is flat, a braided product will result which is also flat, and it is the purpose of this invention to provide an improved mechanism for carrying out the same, whereby in the braiding of a more or less flat filler alternate lengths of the braided product may be produced in which the cross sections vary from that normally produced to one more or less rounded and contracted. Such a product I have found can be produced by using a flat elastic filler tape and by alternately increasing and decreasing the tension exerted on the same so that the tape will alternately be held against folding of its edges under pressure of the braiding threads and relaxed to permit folding under this influence. I have found that particularly good results can be obtained by decreasing this tension suddenly with a subsequent gradual taking up of the relaxation of the filler and the increasing of the tension thereof.

An influence tending to the dependability of and uniformity of the product is the proper deflection thereof in its passing to the take off, which may be accomplished by bending the product from the course and in passing the braiding point over an edge.

A more complete disclosure of the invention will be set forth with reference to the accompanying drawings illustrating an embodiment of my improved mechanism, the novel features of which are particularly pointed out in the appended claims.

In the drawings:

Fig. 1 is a side elevation showing one section of a multi-section braiding machine with the invention applied thereto, the depending end of the filler being twisted from its edge showing to indicate its width, as fully shown in Fig. 6.

Fig. 2 is a partial plan section on the line 2—2 of Fig. 1.

Fig. 3 is an end elevation looking in the direction of the arrow A in Fig. 1.

Fig. 4 is a fragmentary showing of a product of the mechanism illustrated.

Fig. 5 is an enlarged cross section through the braid on line 5—5 of Fig. 4 looking in the direction of the arrow.

Fig. 6 shows a section of the product on the line 6—6 of Fig. 1 showing the operating relation of the slot in the former plate thereto.

The invention will now be described as applied to one section of a multi-section braiding machine, reference being made to the drawings by reference numerals. In these drawings 10 designates a table having race ways 11 formed therein and in which the thread carriers 12 are mounted for travel under the impulse of horn gears 13 actuated through inter-engaging gears 14 connected therewith by sleeves 15 to which both sets of gears are fixed. Extending vertically through the table 10 is a tubular guide 16 having a guide member 16a secured to its upper end which is provided with a guide slot arranged at one side of the bore of the tube as shown in Fig. 1, through which the elastic filler F which is ordinarily in the nature of a flat tape passes vertically to the point at which the braiding takes place, commonly known in the art as the "braiding point"; the braiding being accomplished by the movements of the thread carriers 12 in a well known manner. The slot in member 16a presents a straight edge against the filler, and the elastic filler is shown as being in the nature of a tape fabricated from strands F' of rubber braided together by strands of thread F'', see Fig. 6.

The machine is provided with a horizontally extending bar 17 upon which are mount-

ed for vertical adjustment, the depending brackets 18 which are provided with slot 19 by means of which they are adjustably secured to the bar 17 by the usual connecting means at 19a. To the lower end of each of these brackets is secured a former 20 of usual construction, and having a transverse slot 45 through which the braided product passes on its course from the braiding point to the 10 take off rollers to be described.

Adjustably secured in the slot 19 of bracket 18 is a carrier member 21 on which is pivoted a braid guide member which functions as a tension varying device and is in the nature of a bell crank lever 22, at the free end of one arm of which is secured a peripherally grooved roller 23 over which the braided filler is drawn by take off mechanism to be described, and to the free end of the other 20 arm is pivotally secured an operating rod 24 extending lengthwise of the machine, and operated through suitable mechanism which will now be described.

A bearing bracket 25 is secured to or forms 25 a part of the machine frame in which are journaled shafts 26 and 27; the former shaft having a worm wheel 28 secured to one end, which is driven in synchronism with the movement of the thread carriers through a 30 worm 29 on a vertical shaft 30 having a gear in driven connection with one of the gears 14 through which the horn gears 13, and the thread carriers are operated as set forth above.

35 A longitudinally slotted arm 32 is provided, pivoted at one end to an extension 33 of the bearing bracket 25 as shown at 34, which arm is pivotally and adjustably connected with the extension 24a of the operating rod 24 by means of a bolt 35 extending through the slot in the arm; the extension 24a being also adjustably connected to the rod 24 by a clamp 24b. A roller 36 is also adjustably mounted on the arm 32 by means 40 of a bolt 37 which adjustment together with that between arm 32 and extension 24a may be utilized to effect variations in the throw of the bell crank lever 22 upon operation of the arm 32 under influence of the cam 38 on 45 the periphery of which the roller rides.

The cam 38 is secured to shaft 27 which is driven from shaft 26 through gears 39 and 40 secured to the respective shafts. The cam is provided with a spiral periphery of gradual 50 rise from the low point 38a to the high point 38b between which points there is a sudden drop. The consequence of this arrangement when the mechanism is operating is a sudden relaxation of the tension on the filler F passing 55 through the mechanism followed by a slow recovery thereof compared with the suddenness of the relaxation after which the filler is drawn with uniform tension past the braiding point.

60 The filler F, which is stated above, is in

the nature of a flat elastic tape, is passed through the feed tensioning device or clamp which may be, as shown, in the nature of tension rollers 41 and 42 mounted in a suitable bracket 43 extending from the machine 70 frame, one of the rollers being mounted so that the tension on the filler may be varied as by means of a set screw 44 and in a well known manner. From this tensioning device the filler passes upward through the filler 75 guide 16, slotted guide member 16a, and guide slot 45 in the former 20, which as shown in Fig. 6 presents a straight edge over which the tape bends in passing to and around the roller 23 on the bell crank lever 22 described 80 above; the members 16a and 20 normally tending to maintain the stretched filler in open flat spread relation. The bell crank is mounted to position the roller 23 to one side of the course of the filler through the guide 85 tube and past the braiding point.

The filler as it is drawn along the course defined by this mechanism, is braided normally at a point adjacent to passing through the slot 45 in former 20, and is taken off the 90 machine and deposited in a suitable receptacle 46 by the usual take off rollers 47, 48, 49, journaled in the depending arms 50 extending from the bracket 25. The take off rollers, it will be noted, are laterally spaced from the 95 course of the filler through the tube and past the braiding point oppositely to that of the roller 23. The rollers are provided at their ends with intermeshing gears 60 and are driven through gears 51 on shaft 26 and gear 100 52 on roller 47 through the interposition of gear 53 on the stub shaft 54, which extends from the adjustable arm 55 swingably mounted on shaft 26, and held in adjusted position by bolt 56. The gear 53 is replaceably mounted in order that it may serve as a change speed medium between gears 51 and 52 to vary the speed of travel of the braided filler F through the mechanism as described above. Roller 47 is fixedly journaled in the arms 105 50 while rollers 48 and 49 are adjustably mounted in elongated slots 57 so as to permit adjustment of the tension upon the filler; the rollers being held in adjusted position by set screw 58 extending through ears on roller supports 59, which ride in the slots 57 and the ends of the screws resting on abutments 61 extending from bracket arms 50.

110 During its travel along the course as defined above, the elastic of the filler is normally held stretched flatwise between the tensioning feed mechanism 41, 42, at one end and the take off mechanism at the other end and over the straight edges of the slots in members 16a and 20 as set forth above. As 115 the filler passes along its course it is continuously braided prior to its passage through the slot in the former 20, the braiding point being normally just below the said former. In the meantime cam 38 is continuously ro- 120 125 130

tated in synchronism with the operation of the thread holders and in consequence the bell crank lever 22 is turned on its axis alternately in opposite directions and respectively with a quick and a slow movement, according as the roller 36 is moving between points 38b and 38a, or between points 38a and 39b.

The first of these movements causes a relaxing of the tension of the filler F and the fact that it is held at the feed end by the feed member at 41-42, a consequent dropping of the braiding point results, spacing it a distance below its normal position adjustment the underside of the former. When the filler is passing through the slot 45 under tension and is turned laterally therefrom around the roller 23 it will be held against the straight edge of the slot in member 20 and this relationship will afford sufficient resistance to the tendency of the braiding threads to turn the edges of the filler and fold it upon itself, when the braiding point is normally positioned, but when the roller 36 drops from high point 38b to low point 38a of the cam 38 with a consequent relaxed tension of the filler and a dropping of the braiding point to a level where the resistance to the pull of the threads is relieved, as shown in dot and dash lines in Fig. 1, the filler will be folded upon itself constricting the width of the finished product and producing a rounded construction of more or less oval cross section with tapered junctions between the flat and round portions formed by the folding or spreading filler; said folding being facilitated by the relaxed tension of the filler passing over the straight edge of the slot in member 20. This folding of the filler will continue until the roller 36 has traveled sufficient distance on the rise of the cam to take up the relaxation produced by the drop of the roller as above described and until the braiding point has traveled back to its normal position beneath the former, at which point the edge of opening 45 insures that the stretched filler will resist folding action of the braiding threads and again assume a flat shape. From this point the cam will exert a tensioning influence on the filler which will continue and increase insuring flatwise braiding of the filler until the high point on the cam is again reached, and when the drop of the roller with a consequent slackening of filler will be repeated and with consequent folding of the filler during braiding; this cycle of operations being repeated so long as the machine is in operation.

The effect of this cam action and the distance the braiding point recedes from the former may be varied by adjustment of the roller 36 and of the extension 24a along the arm 32 as set forth above; the distances of the roller and of the nut 35 from the pivotal point 34 of the arm determining the throw

of the bell crank 22 and the consequent amount of slackening of the filler. By this arrangement the proportion of rounded product to the flat may be varied at will between limits for which the machine is constructed, such proportions remaining constant for each adjusted variation.

The mechanism as modified by the present invention is particularly adapted to operation on an elastic filler and produces therewith a uniform and dependable product, although satisfactory results for some purposes may be obtained without the use of an elastic filler. The speed of travel of the filler F through the machine may be varied by interchanging the gears 53 forming the connecting drive between the gear 51 on shaft 26 and gear 52 on the shaft of 47.

While only one embodiment of the invention is herein shown and described, it will be apparent that various changes and adaptations as to detail may be resorted to by one skilled in the art to which the invention appertains, within the principles as herein laid down. I do not wish, therefore, to be limited in the scope of my invention except by disclosures in the prior art and by the scope of the appended claims.

I claim:

1. In combination with a braiding machine comprising a series of circularly traversed braiding carriers and a central vertical guide post for a flat filler; take-off mechanism arranged to continuously feed said filler under tension during braiding of the carrier threads thereon, and means for periodically varying the tension so as to cause periodic foldings of the filler by the braiding threads with resulting narrowings of the product.

2. A mechanism as set forth in claim 1, in which a determinedly rotated cam is arranged to periodically vary the feeding tension of the filler.

3. A mechanism as set forth in claim 1 in which a determinedly rotated cam is adapted to effect a quick reduction in the tensioning of the filler, followed by a gradual increase thereof.

4. A mechanism as set forth in claim 1, in which the take-off mechanism comprises a rockable member over which the covered filler passes from its vertical guide way, and a cam device for rocking said member during the feeding movement of the filler.

5. A mechanism as set forth in claim 1, in which said vertical guide post is provided with a filler-deflecting former plate arranged below the braiding point of the machine, and said take-off mechanism is provided with a product-deflecting rockable member located above said braiding point.

In testimony whereof I affix my signature.
FREDERIC W. PLUMB.
